UNITED STATES PATENT OFFICE.

STEPHEN TOTH, OF FURNACE RUN, PENNSYLVANIA.

GARBAGE-RECEPTACLE.

1,214,389.

Specification of Letters Patent. Patented Jan. 30, 1917.

Application filed July 21, 1916. Serial No. 110,445.

To all whom it may concern:

Be it known that I, STEPHEN TOTH, a subject of the King of Hungary, residing at Furnace Run, in the county of Armstrong 5 and State of Pennsylvania, have invented certain new and useful Improvements in Garbage-Receiptacles, of which the following is a specification.

This invention relates to certain new and 10 useful improvements in garbage receptacles.

The primary object of the invention is the provision of a receiver for garbage and other waste matter which is sanitary and readily operable in both the reception as 15 well as the discharge of the refuse.

A further object of the device is the provision of a receptacle having a normally closed bottom outlet member arranged with a releasing means whereby the contents of 20 the device automatically effects a discharge thereof upon its release, a self-closing receiving entrance means being also arranged.

With these general objects in view and others that will appear as the nature of the 25 invention is better understood, the same consists in the novel construction, combination and arrangement of parts hereinafter more fully described, illustrated in the accompanying drawings, and then claimed.

In the drawings forming a part of this 30 application and in which like designating characters refer to corresponding parts throughout the several views:—Figure 1 is a front elevation of the device partially shown in vertical transverse section. Fig. 2 is a vertical sectional view thereof taken upon line II—II of Fig. 1. Fig. 3 is a top plan view of the same, and, Fig. 4 is an enlarged sectional detail view of the adjacent 35 edges of the bottom doors when closed.

The present device being designed for the 40 reception of refuse, the same includes a receptacle or receiving casing 10 here illustrated substantially cubical in form having off-set supporting legs 11 positioned adjacent each of the four lower corners thereof, side handles 12 being provided for moving the device when found desirable.

A receiving hopper 13 is arranged upon 45 the top 14 of the casing 10 having a forwardly positioned open side or door-way 15 normally closed by means of a swinging door 16 pivoted as at 17 to the said hopper at the upper edge of the door. Closing 50 springs 18 are provided suitably tensioned between the inner face of the door 16 and

the opposite rear wall 19 of the hopper, retaining lugs 20 being provided for the spring upon the said door and hopper as best illustrated in Fig. 2 of the drawing. 55 It will be understood that when it is desired to deposit any matter within the casing 10, the door 16 is pushed inwardly against the action of the springs 18 whereby the matter inserted through the door opening 15 falls into the casing 10 through the opening 21 in the top thereof.

Trap doors 22 constitute the bottom of the casing 10 being hinged as at 23 to the opposite walls thereof, the off-set portions 24 70 of the legs 11 allowing the swinging doors 22 to move to their open positions substantially vertically arranged as illustrated by dotted lines in Fig. 1. A rubber binding strip 25 is carried by the inner edges of each 75 of the doors 22 adapted for contacting each other when the doors are closed forming an air-tight joint between the doors as well as assisting in preventing any escape of odors from the casing 10. 80

A tube 26 is mounted upon the casing top 14 slightly inclined rearwardly through which an operating screw 27 freely extends, a turn nut 28 being threaded upon the outer end of the screw 27 and bearing against 85 the outer end of the tube 26 whereby the said screw is fed outwardly and inwardly as required. An operating handle 29 is provided upon the nut 28 while the screw 27 has its inner end projecting through an 90 opening 30 in the casing top 14. A flexible connector such as a cord 31 connects each of the doors 22 with a ring 32 at the inner end of the screw 27.

The operation of the doors 22 it will be 95 understood is controlled by means of the screw 27 which is normally held projected by means of the nut 28 with the cords 31 in their taut positions, the doors 22 being arranged horizontally in a position to support 100 the entire contents of the casing 10. Upon turning the nut 28 in the desired direction, the screw 27 is lowered allowing the weight of the doors 22 as well as the refuse positioned thereon to forcibly open the said bottom doors, allowing the contents of the casing 10 to pass outwardly through the bottom of the casing to be removed in any manner desirable. 105

It will be understood that the device when 110 filled may be readily carried by means of its handles 12 to a convenient location for

dumping whereupon the doors 22 may be opened and the contents of the casing 10 removed after which the device may be returned to its original location for further use.

What I claim as new is:—

1. A garbage receptacle comprising a casing having bottom members hinged to the opposite sides thereof arranged horizontally when in their normal closed position, supporting legs for the casing having off-set portions adapted for the accommodation of the said doors when in their open substantially vertical position, and releasable closure maintaining means for the said door.

2. A garbage receptacle comprising a casing having bottom members hinged to the opposite sides thereof arranged horizontally when in their normal closed position, supporting legs for the casing having off-set portions adapted for the accommodation of the said doors when in their open substantially vertical position, a tube obliquely positioned upon the said casing, a screw freely extending through the said tube projecting inwardly of the casing, flexible connections between the inner end of the screw and the said doors, and an adjusting nut upon the

said screw revolvably positioned upon the upper free end of the tube.

3. A garbage receptacle comprising a casing, a hopper upon the said casing having a forwardly arranged door opening, a swinging closure door provided for the said opening hinged adjacent the top of the hopper, closing springs for the said door tensioned between the latter and the opposite rear wall of the hopper, bottom outlet doors upon the said casing, and adjustable supporting means for the said doors arranged obliquely rearwardly of the said hopper.

4. A garbage receptacle comprising a casing, a receiving hopper upon the top of the said casing, an automatically closed entrance door for the said hopper, contents supporting bottom doors hinged to the said casing, resilient binding members upon the adjacent edges of the said bottom doors in seating contact with each other when the said bottom doors are in their normal horizontal closed positions, and adjusting means for the said bottom doors operable rearwardly of and in a plane above the said hopper.

In testimony whereof I affix my signature.

STEPHEN TOTH.
